UNITED STATES PATENT OFFICE.

ROBERT D. DONOHUE, OF NEW YORK, N. Y.

FLOWER-WEARING DEVICE.

Application filed December 13, 1923. Serial No. 680,333.

To all whom it may concern:

Be it known that I, ROBERT D. DONOHUE, a citizen of the United States, and resident of the city of New York, in the county of New York and State of New York, have invented a certain new and useful Flower-Wearing Device, of which the following is a specification.

This invention relates to devices intended to aid in the wearing of flowers by providing a means wherewith the stems of the flowers are held together and supported, and a further means wherewith the latter means is secured to the garment of the wearer.

The principal object of my invention is to provide a simplified, inexpensive, conveniently and economically manufacturable, conveniently utilizable, strong, durable, efficient, and improved device for the above mentioned purpose.

Other objects and advantages will herein-after appear.

The invention herein is an improvement upon my previous invention shown and described in my patent application, Serial No. 656,352, filed August 8, 1923.

In the accompanying drawings,—

Fig. 1 shows a front elevation of the device, as it appears when in inoperative state.

Fig. 2 is a side elevation of the device shown in Fig. 1.

Fig. 3 is a plan view of the device shown in Fig. 1.

Fig. 4 is a front elevation of the device, as it appears when holding the flowers or flower in its operative state.

Fig. 5 shows a rear elevation of a modification of the device.

Fig. 6 is an end view of the device shown in Fig. 5.

The device 1, proper, comprises a body portion 2 of suitable metal, which is preferably elongated and concave, in cross-sectional configuration, as shown in Fig. 3, and is provided with two or more wires 3, each of which is independent of the body 2 and the midway portion of which winds around the body in the manner shown in Figs. 1, 3.

The body 2 is provided for each of the wires 3 with pairs of indentations 2^a at the sides thereof, a notch 4 in the front side thereof, and with a wider notch 5 directly at the rear of notch 4 at the opposite or rear side of the body, whereby as the wire 3 is wound there-around, the sides of the coil rest in the indentations 2^a, the peak 6 of the coil is lodged

within the notch 4 while the two wire portions 7 comprising the closed part of the coil are lodged within the wide notch 5, in which manner each of the wires is firmly held in place upon the body against lateral dislocation. Each of the wires 3 is provided at its extreme ends 8 with a spherical enlarged terminal 9. At the rear of the body-portion 2 is located a pin-portion 10, which preferably forms a part of the identical sheet-metal out of which the body 2 is formed, and this pin-portion extends from the upper end of the body-portion. If the body-portion 2 and pin-portion 10 are stamped out of a single piece of sheet-metal, the body portion 2 may be given a medium hardness and the pin portion 10 may be given a spring hardness. The transverse wires 3 are soft, pliable, and readily yieldable.

When using this device the stems 11 of the flowers are placed into the concave side of the body-portion 2, as shown in Fig. 4, and then the wires 3 are bent over the stems and against the body 2, and are twisted around each other, in the manner shown in Fig. 4, whereby the flower stems are firmly held together against the body-portion and are backed and fully reinforced by the latter, and the wires 3 yieldingly adjust themselves to the transverse configuration of the stems and support them firmly and uniformly. The device may be then attached to the garment by means of the pin 10, in the usual effective manner. The body-portion 2 is preferably made in the concave cross-sectional configuration shown to afford a better receiving means for the flower stems. To renew the flowers it merely requires untwisting and bending back of the wires 3 to the position shown in Fig. 1, removing the old flowers and placing back the new, and then securing the new flowers in the manner shown in Fig. 4. When removing the flowers from the lapel it is not necessary to unpin the device from the garment, as the device may continue to stay in its place and the wearer may manipulate the wires 3 by the sense of touch, in which the wearer would be guided by the enlarged spherical terminals 9. The spherical terminals 9 also enable fastening or tying up the wires 3 at their ends, in case a large bouquet is held in the device, by means of a mere twist of the terminals laterally about each other. Said spherical terminals also serve to prevent catching in the garment, add to the better

appearance of the terminals, and aid generally in the manipulation of the wires 3.

Should the wires 3 break or become too kinked after some use, the same may be discarded and a new similar wire substituted, without however requiring renewal of the main or body-portion of the device, and, the wires 3 being cheap, a continuous and very long use may be thus had of the device at only an occasional slight additional expense, the renewal of the wire 3 merely requiring a one-turn twist of the same about the notches 4, 5 of the body 2.

The device shown in Figs. 5, 6 is adapted for use in connection with large bouquets. According to this modification, the body 2 is provided with a plurality of eyes 12, and several wires 13 which thread through said eyes, and their middle portions 14 are disposed against the rear side of the body 2. When using this device, the stems 11 of the flowers are placed against the front concave side 15 of the body-portion, and each of the wires 13 is tied up around the stems 25 of the flowers in the manner shown. The body 2 is provided with a pin 16 which serves for fastening the device to the garment, and it is provided with an auxiliary pin 17, with which it is also secured to the 30 garment and which serves to steady the

device, after it is fastened with the pin 11, so as to maintain the device and the flowers firmly held in place against dislocation in any direction.

Variations may be resorted to within the scope of the invention.

Having thus described my invention, I claim:

1. A flower wearing device having the combination of a body portion for backing the flower stems, a series of openings at each side of said body portion, and a wire disposed against the rear of said portion and passing, through said openings for fastening the stems to said portion. 45

2. A flower wearing device having the combination of a body portion for backing the flower stems, a series of openings at each side of said body portion, a wire disposed against the rear of said portion and 50 passing through said openings for fastening the stems to said portion, and said wire having enlarged terminals to facilitate its manipulation.

Signed at the city of New York in the county of New York, and State of New York, this 11th day of December A. D. 1923.

ROBERT D. DONOHUE
